CLAIM

The ornamental design for an illuminated sign as shown and described.

DESCRIPTION

FIG. 1 is a front perspective view of an illuminated sign, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a front perspective view of an illuminated sign shown in an environment of use.

The broken lines depict portions of the illuminated sign or environmental subject matter only and form no part of the claimed design.

1 Claim, 8 Drawing Sheets
